VENETIAN BLIND

Louis Mintz, Cleveland, Ohio

Application September 27, 1937, Serial No. 165,804

1 Claim. (Cl. 156—17)

This invention relates to Venetian blinds and has for its object to provide such a blind with a supporting bar which is formed to provide a housing for the blind operating mechanism which provides a rigid support for the blind which is of pleasing appearance and which can be economically manufactured.

A further object is to provide a combined supporting bar and housing for the blind operating mechanism which is formed of a material which matches the material of the slats which is of a thickness corresponding substantially to the width of the slats and which is so constructed that when mounted in a window frame it effectually conceals the blind operating mechanism.

With the above and other objects in view the invention may be said to comprise the device as illustrated in the accompanying drawing, herein-after described and particularly set forth in the appended claims, together with such variations and modifications thereof as will be apparent to one skilled in the art to which the invention appertains.

Reference should be had to the accompanying drawing forming a part of this specification in which

Figure 1 is a front elevation of a Venetian blind embodying the invention;

Fig. 2 is a front elevation of the supporting bar which provides the housing for the blind operating mechanism, a portion of the bar intermediate its ends being broken away to show the mechanism mounted within the bar;

Fig. 3 is a top plan view of the supporting bar;

Fig. 4 is an end elevation of the supporting bar viewed as indicated at 4—4 in Fig. 2;

Fig. 5 is a section taken on the line indicated at 5—5 in Fig. 2;

Fig. 6 is a section taken on the line indicated at 6—6 in Fig. 2;

Fig. 7 is a side elevation of the guiding and locking device for the blind lifting cables;

Fig. 8 is an end elevation of the device shown in Fig. 7;

Fig. 9 is a side elevation of one of the bar-supporting brackets; and

Fig. 10 is a section taken on the line indicated at 10—10 in Fig. 9.

In Fig. 1 of the accompanying drawing a Venetian blind embodying the invention is shown mounted upon the interior of a window frame 1, the blind comprising a top bar 2, slats 3 connected to suitable slat-tilting strips 4 of fabric or other suitable flexible material. The strips 4 extend vertically along opposite sides of the blind

and are connected to opposite edges of the slats 3 so that, by raising the strips on one side and lowering the strips on the other side, the slats 3 may be tilted to the desired angle. The upper end of the strips 4 are attached to drums 5 which are mounted upon a shaft 6 so that, when the shaft is turned in one direction or the other, the drums 5 turning with the shaft operate the strips 4 to tilt the slats 3. The shaft 6 carries a worm gear 7 which meshes with a worm 8 to which is attached a sheave 9 operated by a cable 10. The ends of the cable 10 extend downwardly from the sheave 9 and the ends of the cable may be provided with handles 11. By means of the cable 10 the shaft 6 may be turned in one direction or the other to impart the desired angle of tilt in either direction to the slats 3.

Within the drums 5 pulleys 12 and 13 are pivotally suspended from the shaft 6 and receive cables 14 and 15 which extend down to the bottom bar of the blind adjacent opposite ends thereof. By pulling on the cables 14 and 15 the blind is raised, collapsing the slats 3. Upon release of the cables 14 and 15 the blind is lowered by gravity. The drums 5 are provided with slots 16 which accommodate the cables 14 and 15 in any angular position of the drums. The cables 14 and 15 extend over pulleys 17 mounted in an end of the bar 2 beyond the end of the shaft 6 opposite that at which the cable 10 is located. The raising and lowering of the blind is accomplished by operating the cables 14 and 15, while the tilting of the slats is accomplished by the cable 10 in the usual and conventional manner.

The supporting bar 2 is a one-piece bar of rectangular cross section, preferably composed of a material similar to that of the slats 3, so that when painted the external appearance of the bar will correspond to that of the slats 3. The thickness of the bar 2 corresponds substantially to the width of the slats 3 so that, when the slats are collapsed against the bottom of the bar 2 the edges of the slats are substantially flush with the outer face of the supporting bar 2. It is preferred to construct the slats 3 and also the supporting bar 2 of wood. The side faces of the bar 2 are continuous smooth faces having no apertures or parts attached thereto, and the bar 2 is of a length to extend substantially the full length of the space between the side members of a window frame.

In order to house the actuating mechanism within the bar 2 the bar is provided with drum-receiving recesses 18 and 19 which are spaced from the ends of the bar and which are spaced from

each other. The recesses 18 and 19 are of a width and depth such as to provide fairly thin bottom and side walls at the bottom and sides of the bar. The rigidity and strength of the bar is maintained, however, by reason of the fact that beyond the ends of the recesses 18 and 19 and between the recesses 18 and 19 the bar is weakened very little. The short thin-walled portions of the bar providing the bottoms and sides of the chambers 18 and 19 are of relatively short length and, since these thin-walled portions of the bar alternate with relatively stiff portions of the bar, the bar is not greatly weakened by the mechanism-receiving recesses. By reason of its construction 15 as above described the bar of the present invention needs to be of a width and depth but little greater than the drum diameter and has sufficient strength to support a wide blind without intermediate supports or braces.

20 Between the recesses 18 and 19 the bar is provided with a narrow channel 20 of less depth than the recesses 18 and 19 to receive the shaft 6 and the cable 14. The thick walls at opposite sides of the central channel 20 greatly stiffen the 25 sides of the bar 2 and the thickened portion at the bottom of the channel 20 greatly stiffens the bottom wall of the bar. The drum recesses 18 and 19 are provided with cable openings 21 directly beneath the shaft 6 through which the slot-lift- 30 ing cables 14 and 15 pass. At opposite sides thereof the recesses 18 and 19 are provided with slots 22 through which the slat-tilting strips 4 pass. The recess 18 is provided in the bottom with a slot 23 through which the cable 10 extends.

35 The shaft 6 is journaled at one end in a bracket 24 which is secured to the bottom of the recess 18 by means of screws 25 and the opposite end of the shaft is journaled in a bracket 26 secured by screws 27 to the bottom of the recess 19. The screws 25 and 27 are accessible from the open top of the recesses 18 and 19 so that the shaft 6, drums, and shaft-operating gearing can be removed as a unit from the housing bar 2. The 40 recesses 18 and 19 are of a depth such that the tops of the drums 5 are below the plane of the top surface of the bar, so that the actuating mechanism is completely housed within the bar and completely concealed when the blind is placed in the window frame.

45 The guard pulley 17 for the cables 14 and 15 is mounted in a U-shaped bracket 28. The end of the bar in which bracket 28 is mounted is provided with a laterally inclined slot 29 within 50 which the U-shaped bracket 28 fits. The bracket 28 is of a width just sufficient to accommodate the roller 17, which is just wide enough to receive the two cables 14 and 15. The lateral inclination of the roller 17 is such as to permit the convenient lifting of the blind by a pull on the cables 14 and 15 in a direction inclined outwardly from the vertical. The free ends of the U-shaped brackets 28 are provided with horizontal flanges 55 30 which rest upon shoulders on opposite sides of the upper edge of the inclined slots 29 which are provided by a wide channel in the top part of the bar. The bracket is secured in place by means of screws 31 securing the flanges 30 to the shoulders on which they rest. The screws 31 60 are also accessible from the top of the bar so that the bracket 28 is readily removable. The bottom of the U-portion of the bracket is slightly above the bottom plane of the bar, so that the bracket 28 is entirely concealed when the blind is in place

in the window frame. The bracket 28 also reinforces the slotted end of the bar 2.

To keep the cables 14 and 15 side by side upon the pulleys 17 the bottom of the bracket 28 is provided with a central finger 32 which projects 5 inwardly beneath the pulley 17 between the two cables 14 and 15. Means are provided for locking the cables 14 and 15 in the pulley 17 in any position of adjustment of the blind. The locking of the cables is effected by the shifting of the 10 cables 14 and 15 laterally toward the adjacent edge of the blind after the desired adjustment is made. The locking member is a knurled roller 33 which is journaled in a U-shaped arm 34 which is mounted to swing upon a pivot 35. The pivot 15 35 is mounted in the bracket 28 outwardly of the pulley 17. The knurled roller 33 normally rests upon the bottom of the bracket 28, in which position of the roller the supporting arm 34 is inclined downwardly and inwardly from the pivot 20 35. In this position of the knurled roller its periphery is closely adjacent the cables 14 and 15 when the same are hanging vertically down from the pulley 17. When the cables 14 and 15 are moved outwardly against the knurled roller 25 33 they frictionally engage with the periphery of the roller 33 and, as the cables move upwardly, cause the roller 33 to press the cables 14 and 15 against the periphery of the roller 33 to press the cables 14 and 15 against the periphery of the roller 33 to press the cables 14 and 15 against the periphery of the 30 roller 17, firmly clamping the cables 14 and 15 against further movement. Upward movement of the arm 34 is limited by a lug 36 formed integrally with a side wall of the bracket 28. The lug 36 prevents upward movement of the arm 34 35 beyond the clamping position.

The mechanism housing bar 2 has a close fit within the upper portion of a window frame so that the top bar of the window frame will form a closure for the open top recesses in the bar in 40 which the operating mechanism is mounted. The bar 2 is supported by two rectangular thin metal brackets 37 secured in the upper inner corners of the window frame. The brackets 37 have flat side portions secured by screws 38 to the side 45 bars of the window frame and are provided with short inwardly extending flanges 39 along the top, rear and bottom margins thereof, the front of these brackets being open to receive an end of the bar 2. The length of the bar 2 is such as to fit snugly between the side faces of the brackets 37 and the depth of the bar is such as to fit snugly between the top and bottom flanges of the brackets. Adjacent each end the bar 2 is provided on the under side with a projecting pin 40 50 which enters a slot 41 in the bottom flange of a supporting bracket and each bracket is provided with a hook 42 adapted to be moved into engagement with a pin 40 to lock the bar in the bracket.

Furthermore, it is to be understood that the 60 particular apparatus shown and described is presented for purposes of explanation and illustration and that various modifications can be made without departing from my invention as defined in the appended claim.

What I claim is:

In a Venetian blind of the type provided with lifting cables and slat-tilting drums carried by a shaft and connected through flexible members to the slats, a combined mechanism housing and 70 head bar comprising a wood bar having mechanism-receiving recesses routed out from the top face thereof and openings through its bottom face for said cables and flexible members, said recesses comprising drum-receiving recesses spaced 75

apart longitudinally and located inwardly of the ends of the bar and a narrower and shallower shaft-receiving recess across the space between the drum recesses, said drum-receiving recesses being of a width and depth to provide drum-receiving chambers with relatively thin side and bottom walls, said bar having rigid end portions

and a rigid portion of substantial length between the drum recesses, the relatively short thin-walled portions being interposed between and integral with more rigid portions of the bar whereby a housing and supporting bar of relatively small size and great rigidity is provided.
